SPARK PLUG ELECTRODE STRUCTURE

Tullio Tognola, Sidney, N. Y., assignor to Bendix Aviation Corporation, New York, N. Y., a corporation of Delaware

Application July 7, 1943, Serial No. 493,777

9 Claims. (Cl. 123—169)

1

This invention relates to ignition apparatus for internal combustion engines or the like and more particularly to spark plugs and parts thereof.

It is a well and universally known fact that the electrodes of a spark plug between which the spark or electric arc is created within an engine cylinder are the first elements of a well constructed spark plug to deteriorate from use and to thereby render the spark plug inefficient or wholly ineffective or inoperative. It is accordingly an object of the present invention to provide a novel electrode structure for a spark plug whereby the useful life of the latter may be materially extended.

Another object of the invention is to provide novel means for restoring to usefulness a deteriorated electrode of a spark plug without appreciably disturbing the remainder of the spark plug structure.

Still another object is to provide a novel method of reconditioning a used electrode in an assembled spark plug or separable unit thereof.

A further object is to provide a novel electrode structure in a spark plug whereby the portion thereof which wears out readily in use may be inexpensively replaced and in such a manner as to restore the original efficiency and effectiveness of the spark plug.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention, reference for this latter purpose being primarily had to the appended claims.

In the drawings, wherein like reference characters refer to like parts throughout the several views,

Fig. 1 is an enlarged side elevation, partly in section and with parts broken away, of one form of spark plug to which the present invention is applicable;

Fig. 2 is a bottom view of the spark plug shown in Fig. 1; and,

Figs. 3, 4 and 5 are detail views, partly in section and with parts broken away, showing the center electrode of the spark plug of Fig. 1 in various stages of completion and illustrating the steps in the novel reconditioning process comprehended by the invention.

The single embodiment of the invention illustrated in the drawings is shown, by way of example, as applied to a radio-shielded spark plug

2

with mica insulation—a type of spark plug which is well-known in the art and widely used on present day aircraft engines. It will be understood, however, that the invention is equally applicable to unshielded spark plugs and to others constructed with other types of insulation, such as ceramics or like materials.

The spark plug shown in the drawings comprises a shell 10 which is provided with external threads 11 for threaded engagement with an opening in an engine cylinder (not shown). Extending upwardly from shell 10 and formed integrally therewith or secured thereto in any suitable known manner is a shielding barrel 12 which, as pointed out above, is not a necessary element of the invention. Suitably mounted in shell 10 and barrel 12 in any of many well-known ways is a center electrode assembly comprising a center electrode 13 which is insulated from shell 10 by some suitable insulating material, such as mica sleeve 14 and mica washers 15. The details of the center electrode assembly may, for example, be of the character disclosed in Tognola Patent No. 2,300,714.

In the illustrated embodiment, center electrode 13 comprises a spindle 16 which is surrounded by mica sleeve 14 and a head or tip which, in turn, consists of a cylindrical portion 17 and a frustro-conical portion 18. The latter portion preferably has its conical surface in parallel and spark gap relation to a plurality of bendable prongs 19 of a ground electrode 20, which is secured in the lower end of shell 10, preferably in the manner disclosed in Kishbaugh U. S. Patent No. 2,300,730.

During operation of the spark plug described above, the rapid succession of sparks between prongs 19 and tip portion 18 of the center electrode under high heat and pressure in an atmosphere of combustible vapor causes relatively rapid erosion of the adjacent surfaces of these parts. Up to a certain extent, this erosion may be partially and satisfactorily corrected by bending the prongs 19 inwardly to insure the proper spark gap.

Prior to conception of the present invention, it was the usual practice when this adjustment would no longer compensate for the wear or erosion to discard the entire spark plug or to at least disassemble and rebuild the entire structure. The novel construction contemplated by the present invention makes it possible to readily and inexpensively recondition such used spark plugs and render the same substantially as efficient and durable as new structures.

In the process of reconditioning contemplated,

the center electrode assembly is first removed from shell 10 as the same is of the removable type, or the ground electrode 20 is merely removed from the shell to permit access to the nose portion of the center electrode assembly. In instances where the erosion of tip 18 is not too severe, it is only necessary to machine this portion of the electrode to remove the pits and deep blemishes by increasing the angle of the external surface thereof. If the surface does not clean up before the smallest diameter of the tip is reduced to a predetermined minimum, which varies in different sizes of spark plugs, the necessity of retipping in accordance with the present invention is indicated.

Retipping of the center electrode is preferably effected by first machining or turning down the frustro-conical tip 18 or corresponding portion of other types of electrodes to form a substantially cylindrical stem or post 21, as illustrated in Fig. 3. A small recess or counter-bore 22 is then drilled in the end of said stem and the surfaces of said stem and electrode portion 17 are coated with a suitable soldering flux. Thereafter, a quantity of solder, such as silver solder, which is preferably in the form of a thin washer 23, is put in place and a new tip member 24 of suitable electrode metal is placed over stem 21. Said member is preferably cylindrical, as shown in Fig. 4, the same having an external diameter substantially equal to the diameter of head portion 17 of the electrode and an internal diameter only slightly larger than the diameter of post 21. At its outer end, the bore through member 24 is enlarged slightly to form a conical recess 25, as best seen in Fig. 4.

After the parts have been assembled, as illustrated in Fig. 4, the outer end of stem 21 is spun outwardly in the manner illustrated in Fig. 5 to provide a mechanical lock for holding member 24 in place and prevent any possibility of the same coming loose and dropping out. The tip or nose portion of the electrode is then heated to approximately 1400° F., depending upon the melting point of the solder used. In order to localize the heating and thus avoid damage to the remainder of the electrode assembly, electrical induction heating is employed. This type of heating with a "Lepel" machine also insures rapid penetration of the heat to the center of the tip assembly. While the assembly is heated, additional solder is put on the end of the electrode assembly to fill recess 22 and flow into the bore of member 24 around stem 21. While the solder, including washer 23, is in melted condition, manual or mechanical pressure is applied with a suitable tool which simultaneously presses member 24 against the surface of tip portion 17 and further spreads the outer end of stem 21. The application of the pressure is preferably continued until after the assembly has cooled to a temperature below the melting point of the solder employed. During the application of this pressure, solder from washer 23 is forced into the bore of member 24 around core 21. Substantially all adjacent surfaces of member 24 and electrode portions 17 and 21 are intimately secured to one another by high heat conducting solder.

When the assembly has been cooled to room temperature, member 24 is machined or turned down to the same dimensions as the corresponding portion of a new spark plug and the outer end of the electrode is faced off. If desired, of course, the tip member 24 may be partially ma-

chined before it is secured in place on the center electrode assembly. It will also be understood that the center electrode structure illustrated in Fig. 5 is applicable to new spark plugs as well as to reconditioned spark plugs. When electrode member 24 becomes worn or eroded, the same may be removed and a new one installed in its place. When the new tip piece 24 has been installed and machined to proper dimensions, a new ground electrode 19, 20 may be secured in position in shell 10. Where the shell is removable from the center electrode assembly or unit, the new ground electrode may be put in at any time.

There is thus provided a spark plug which embodies a novel center electrode structure which may be incorporated either in a new spark plug or in a used one—in the latter case to restore an eroded center electrode to efficient operating condition. Additionally, the invention contemplates a novel structure and a method of constructing the same which facilitate restoration of used or worn out spark plug electrodes without appreciably disturbing the major assemblies of the spark plug structure. The method and novel structure contemplated also reduce to a minimum the operating cost of engines insofar as spark plugs are concerned, without any reduction in operating efficiency.

Although only a single embodiment of the invention is illustrated and described in the foregoing specification, it is to be expressly understood that the invention is not limited thereto. For example, as heretofore pointed out, the invention is applicable to other types of spark plugs having different types of insulation and electrode structures. Various changes may also be made in the design and arrangement of parts illustrated without departing from the spirit and scope of the invention, as will now be understood by those skilled in the art. For a definition of the limits of the invention, reference is had primarily to the appended claims.

What is claimed is:

1. In a spark plug for internal combustion engines or the like, a center electrode comprising an elongated spindle and a head on said spindle at one end thereof, said head comprising an enlarged portion integral with said spindle, a stem portion integral with said enlarged portion, said stem portion being coaxial with said spindle and at the opposite side of said enlarged portion, a tip member surrounding said stem portion, and means for securing said tip member to said stem portion and said enlarged portion.

2. In a spark plug for internal combustion engines or the like, a center electrode comprising an elongated spindle and a head at one end thereof, said head comprising an enlarged disc-like portion integral with said spindle, a stem integral with said disc-like portion and coaxial with said spindle, a tip piece around said stem and butting against said disc-like portion, and fusible means for securing said tip piece to said stem and disc-like portion.

3. In a spark plug for internal combustion engines or the like, a center electrode structure comprising an elongated spindle and a head at one end of said spindle, said head comprising an enlarged disc-like portion integral with said spindle, a stem integral with said disc-like portion and extending in the opposite direction from said spindle, a tip piece surrounding said stem, and means including a fusible metal for securing said tip piece to said disc-like portion and said stem.

4. In a spark plug for internal combustion engines or the like, a center electrode structure comprising an elongated spindle and a head at one end of said spindle, said head comprising an enlarged disc-like portion integral with said spindle, a stem integral with said disc-like portion and extending in the opposite direction from said spindle, and a tip piece surrounding said stem, a portion of said stem being pressed outwardly into overlapping relation with said tip piece to mechanically lock the latter in position on said structure.

5. In a spark plug for internal combustion engines or the like, a center electrode structure comprising an elongated spindle and a head at one end of said spindle, said head comprising an enlarged disc-like portion integral with said spindle, a stem integral with said disc-like portion and extending in the opposite direction from said spindle, a tip piece surrounding said stem, a portion of said stem being pressed outwardly into overlapping relation with said tip piece to mechanically lock the latter in position on said structure, and fusible means for connecting the adjacent surfaces of said piece and said stem and disc-like portion.

6. A center electrode for a spark plug comprising an elongated spindle, a stem portion coaxial with said spindle, an enlarged disc-like portion between adjacent ends of said spindle and stem 30 and integral therewith, a tip piece having a bore therethrough for receiving said stem, and fusible means for securing said tip piece to said stem and disc-like portions.

7. A center electrode for a spark plug comprising an elongated spindle, a stem portion coaxial with said spindle, an enlarged disc-like portion

between adjacent ends of said spindle and stem and integral therewith, a tip piece having a bore therethrough for receiving said stem, and means for securing said tip piece in position including fusible means between said tip piece and the adjacent surfaces of said stem portion and said disc-like portion.

8. A center electrode for a spark plug comprising an elongated spindle, a stem portion coaxial with said spindle and having a recess in one end thereof, an enlarged disc-like portion between adjacent ends of said spindle and stem, and a tip piece having a bore therethrough for receiving said stem, the recessed portion of said stem being spun outwardly into locking engagement with said tip piece.

9. A center electrode for a spark plug comprising an elongated spindle, a stem portion coaxial with said spindle and having a recess in one end thereof, an enlarged disc-like portion between adjacent ends of said spindle and stem, a tip piece having a bore therethrough for receiving said stem, the recessed portion of said stem being spun outwardly into locking engagement with said tip piece, and fusible means for joining said tip piece to said stem and disc-like portion.
